[57] CLAIM

The ornamental design for a push broom, as shown and described.

DESCRIPTION

FIG. 1 is a top, front and end perspective view of a push broom showing my new design;

FIG. 2 is a top plan view thereof, the handle being shown broken away for ease of illustration only;

FIG. 3 is an end elevational view thereof, the opposite end being a mirror image;

FIG. 4 is a rear elevational view thereof; and

FIG. 5 is a bottom plan view thereof.

FIG. 1

FIG. 2

FIG.3

FIG. 4
